[57] CLAIM

The ornamental design for a wrist watch, as shown and described.

DESCRIPTION

FIG. 1 is a top, front and left side perspective view of a wrist watch showing our new design, with the band omitted for ease of illustration;

FIG. 2 is a top plan view, with the band;

FIG. 3 is a bottom plan view of FIG. 2;

FIG. 4 is a left side elevational view of FIG. 2;

FIG. 5 is a right side elevational view of FIG. 2;

FIG. 6 is an inverted rear elevational view of FIG. 2; and

FIG. 7 is a front elevational view thereof, of FIG. 2.

FIG. 1

FIG. 2

FIG. 3
